CIRCUIT INTERRUPTER.

Andrew H. Bakken, Edgewood, Pa., assignor to
Westinghouse Electric & Manufacturing Com-
pany, East Pittsburgh, Pa., a corporation of
Pennsylvania

Application September 21, 1938, Serial No. 230,948
Renewed November 15, 1939

18 Claims. (Cl. 200—150)

This invention relates to high-voltage, high-power circuit interrupters and more particularly to improvements in the housing structures therefor. Arc extinction in high-power circuit interrupters of either the gas blast or liquid immersed type is accompanied by the generation of arc gases in quantities which cause considerable pressure within the interrupter housing. During the interruption of extremely severe short circuits or short circuits of lesser magnitude, but of considerable duration, the pressure produced may exceed the safe limits of the housing in that inadequate means, in the form of a breather or muffler, are provided to relieve the pressure. The provision of pressure relieving means, in addition to the conventional breather or muffler, is of particular importance in breakers of the porcelain-clad type, wherein the housing structure is composed largely of insulating material and, therefore, more subject to failure as a result of high pressure during arc extinction.

The present invention has for its object the provision of a circuit breaker housing which is capable of quickly relieving the pressure generated therein even during the interruption of sustained short circuit currents of extremely large magnitude.

A further object of my invention is the provision of a circuit breaker in which the relief of pressure is controlled by the same resilient means which is utilized in moving the breaker contact structure to the open circuit position, but which is independent of the breaker contact position.

Other objects and advantages will appear more fully in the following description when taken in connection with the accompanying drawings, in which:

Figure 1 is a side view, partially in section, of a circuit breaker illustrating an embodiment of my invention;

Fig. 2 is a sectional view of the upper portion of the circuit breaker of Fig. 1 on a larger scale, showing the interrupter in the closed circuit position and the pressure relieving structure in its normal position;

Fig. 3 is a sectional view similar to Fig. 2 showing the interrupter in the open circuit position and the pressure relieving structure in the operative position;

Fig. 4 is a cross-sectional view of the interrupter shown in Fig. 2 taken along the line IV—IV;

Fig. 5 is a cross-sectional view of the interrupter shown in Fig. 2 taken along the line V—V; and

Fig. 6 is an exploded perspective view of the linkage mechanism utilized in operatively coupling the pressure releasing cap of the breaker housing with the main operating spring of the breaker.

Referring to the drawings, the reference numeral 10 designates a metallic casing having a top support plate 12 which carries a tubular insulator 14 of porcelain or other weatherproof insulating material. The upper end of the insulator 14 has an annular metallic plate 16 seated thereon which carries a dome-like closure comprising a cylindrical metallic section 18 and a cap-like metallic member 20. The cap member 20 is yieldingly maintained in position with respect to the cylindrical section 18 in a manner and for a purpose which will be more fully described hereinafter.

Disposed within the tubular insulator 14 is a tubular support and strain member 22 of insulating material having a metallic collar 24 secured to each end thereof. The lower collar 24 in cooperation with bolts 26 serves to rigidly secure the strain member 22 to the supporting plate 12. The upper collar member 24 is secured by bolts 28 to an annular support plate 30, which in turn is bolted to the annular plate 16. The relative lengths of the tubular insulator 14 and the tubular strain member 22 are such that when the securing bolts 28 are drawn towards clamping engagement with the upper collar 24, the strain member 22 will be placed in tension, and the tubular insulator 14 will be placed in compression. The strain member 22, in that it is securely fastened at its lower end to the support plate 12, also carries all lateral stress which may be placed upon the interrupter housing, thereby relieving the external insulator 14 of all stresses except those which arise in compression.

A circuit interrupting unit generally shown at 32 is disposed within the tubular strain member 22 and consists of two interrupting elements 34 and 36 arranged for series operation. The upper end of the interrupting element 34 is provided with a flanged metallic casing 38 having four laterally extending support arms 40. The support arms 40 provide the sole support for the interrupting unit 32, and are adapted to be secured to the support plate 30 by means of bolts 42 as shown. Thus the entire interrupting unit may be removed from the interrupter housing by merely removing the four bolts 42.

The circuit interrupting unit 32 and the method of mounting the same with respect to the interrupter housing are clearly shown and de-

scribed in the copending application of B. P. Baker, Serial No. 230,946, filed September 21, 1938, and assigned to the assignee of this application.

5 As shown and described in the aforesaid application and in Figs. 2 and 3 of the instant application, the interrupting element 34 comprises an outer casing 44 of insulating material having a plurality of washers 45 and 46 of different internal diameter alternately disposed in the lower end thereof, so as to form a corrugated arc chamber 48. The upper end of the casing 44 in conjunction with the flanged casing member 38 form an expansion chamber 50 in which are disposed a plurality of fixed contact fingers 52. The contact fingers 52 are connected by means of flexible shunts 54 to the flanged casing member 38.

10 A movable operating member 56 extends axially through the arc chamber 48 and the expansion chamber 50, and is provided with a contact ring 58 adapted to engage the fixed contact fingers 52 when in the closed position, as shown in Fig. 2. The operating member 56 also carries a plurality of washers 60 and 61 of different diameters 15 and which are alternately disposed so as to form a corrugated section of insulating material which serves as a follow-up member for restricting and limiting the dimensions of the arc chamber 48 when the operating member is moved to the open 20 circuit position.

15 The construction and arrangement of the interrupting element 36 is similar to that of the element 34 above described. The movable elements of the interrupter 36, such as the contact ring 58 and the corrugated section of insulating material, are also carried by the operating member 56.

20 A series connection between the elements 34 and 36 is effected by a conducting sleeve 63 carried by the operating member 56, which sleeve joins the contact ring 58 of the element 34 and is, in turn, connected to the contact fingers 52 of the interrupting element 36 by flexible shunts 59. An external circuit connection is made to 25 the upper end of the interrupting unit 32 by means of a flexible connector 63 joining the flanged casing 38 and a line terminal 65 passing through the side of the cylindrical casing 18. A line terminal 67 extending through the casing 10 and connected by a flexible connector 69 to the lower end of the operating member 56 provides the external circuit connection to the other end of the interrupting unit 32. Thus the electrical circuit through the interrupter proceeds from the 30 upper line terminal 65 through the connector 63 to the flanged casing 38, the flexible shunts 54, the contact fingers 52, the movable contact ring 58, the conducting sleeve 61, the flexible shunts 59 and then through the contact fingers and the 35 contact ring of the interrupting element 36, the lower end of the operating member 56, the connection 69, and terminates at the line terminal 67.

35 It will be noted that the contact ring 58 adjacent the left-hand contact finger 52, as shown in Fig. 2, is extended outwardly and has considerably greater width than the portion adjacent the right-hand contact finger 52. This arrangement, during the opening operation of the interrupter, causes the left-hand contact finger 52 to separate last in point of time from the contact ring 58, thereby causing the arc to be drawn between the left-hand contact finger 52 longitudinally of the arc chamber 48, and to be confined in the comparatively narrow passage between the fixed washers 45 and 46 and the mov-

able washers 60 and 61 carried by the operating member 56.

40 The downward movement of the operating member 56 to the open circuit position, as shown in Fig. 3, also causes a flow of arc extinguishing liquid longitudinally of the arc to bring about arc extinction in a manner more fully described in the aforesaid application. Movement of the operating member 56 to the open circuit position is effected by a battery of compression springs 62 arranged in the dome-like closure of the casings 18 and 20. The springs 62 are disposed between an upper pressure plate 64 and a lower pressure plate 66, each of which are guided for reciprocating movement upon the guide and support rods 18 68, the lower ends of which are respectively secured to the four supporting arms 40 carried by the flanged casing 38. The upper ends of the guide rods 68 are united with a stop plate 70 towards which the pressure plate 64 is urged by the springs 62. The lower pressure plate 66 is secured to the upper end of the operating member 56. The operating member 56 is moved to the closed circuit position against the tension of the springs 62 by a suitable straight-line operating mechanism generally indicated at 72 disposed in the casing 18. Upon release of the operating member 56 by the operating mechanism 72, the compression springs 62 drive the pressure plate 66 and the operating member 56 20 downwardly to the open circuit position, thereby establishing an arc in each of the arc chambers 48 and bringing about circuit interruption.

25 The circuit interrupting elements 34 and 36 are provided with a vent opening 74 for the escape of the products of decomposition of the arcs drawn therein into the space within the tubular strain member 22 and the dome-like closure thereabove. In the event that the arc-ing is severe or unduly prolonged, considerable 30 pressure is generated within the tubular strain member 22. In order to relieve the interrupter housing of abnormal pressure, provision is made for resiliently supporting the cap member 20 upon the cylindrical closure member 18, whereby 35 the cap member 20 will be raised sufficiently to permit gas and arc extinguishing liquid to escape between the separating edges of the sections 18 and 20.

40 The mechanism for maintaining the cap member 20 in position with respect to the cylindrical section 18 comprises a bolt 76 passing through a metallic bushing 78 secured to the upper end of the cap member 20. The lower end of the bolt 76 has a square head 80, and is adapted to fit in a square recess 82 provided in the stop plate 70. Surrounding the bolt 76 and secured to the stop plate 70 is a box-like support 84, the four sides of which respectively parallel the four sides in the square aperture 82. Each side of the support 84 is provided with a rectangular aperture 86 adjacent the stop plate 70 for the reception of a lever 88. The inner ends of the levers 88 are adapted to rest upon the shoulders of the square head 80 of the bolt 76. The outer ends of the levers 88 are provided with a conical recess 90 into which the ends of pivotal bolts 92 are seated. The bolts 92 are supported by and screw threaded through the moving pressure plate 64, and are provided with lock nuts 94 for the purpose of locking the bolts in position with respect to the pressure plate 64 when the proper adjustment has been made.

45 From the foregoing description it is apparent that the mechanism for holding the cap member 75

28 into engagement with the cylindrical section 18 constitutes a simple lever arrangement, the operation of which is as follows: The holding bolt 76 is placed under tension by means of a nut 96 threaded on the upper end thereof so as to cause the head 86 to raise the inner ends of the levers 88 against the upper edge of the apertures 86 in the box-like support 84. This causes the outer ends of the levers 88 to move 10 downwardly and exert a force upon the pivotal support bolts 92. Since the pivotal support bolts 92 are carried by the movable pressure plate 64, which, in turn, is engaged by the compression springs 62, the compression springs will oppose 15 the force exerted by the tension in the bolt 76 to resiliently hold the cap member 20 in engagement with the cylindrical section 18. Thus in the event that the pressure within the interrupter housing exceeds a predetermined value, 20 the cap member 20 will be raised from its seat upon the cylindrical section 18 against the compressive action of the springs 62. Inasmuch as the pressure plate 64 engages the upper end of the spring 62, the springs 62 may be utilized for 25 resiliently holding the cap member 20 in position independently of the position of the lower movable pressure plate 66 and the operating member 56. In other words, the compression springs 62 constantly exert a biasing force for maintaining 30 the cap 20 in position irrespective of the position of the operating member 56. The pressure acting upon the cap member 20 during circuit opening operation also reacts to cause the upper pressure plate 64 to move downwardly so as to 35 increase the force tending to move the operating member 56 to the open circuit position. In order that the cap member will automatically align itself with respect to the cylindrical section 18, the lower end of the cap member is provided 40 with a conically flanged seat surface 98, as shown in Figs. 1 to 3 of the drawings.

Although I have shown and described a specific circuit breaker structure, it is to be understood that the same is for the purpose of illustration and that changes and modifications may be made 45 by those skilled in the art without departing from the spirit and scope of the appended claims.

I claim as my invention:

1. In a circuit interrupter, a housing, circuit 50 interrupting means within said housing, said circuit interrupting means including a pair of contacts at least one of which is movable for establishing an arc, resilient means for biasing said movable contact to the open circuit position, and 55 pressure relieving means associated with said housing including a member movable to open and closed positions, said movable member being normally biased to the closed position by said resilient means and moved to the open position 60 in response to predetermined pressure conditions within said housing.

2. In a circuit interrupter, a housing including two separable sections, resilient means for normally holding said separable sections together, 65 separable contacts within said housing, and actuating means including said resilient means for operating said contacts to the open circuit position to establish an arc, said resilient means enabling said separable sections of said housing to 70 move apart in response to predetermined pressure conditions within said housing.

3. In a circuit interrupter, a housing having a vent opening, a closure member for said opening movable to open and closed positions, spring 75 means biasing said closure member to the closed

position, contact means within said housing, and an actuating mechanism including said spring means for operating said contact means to establish an arc within said housing, said closure member being movable to the open position 5 against the bias of said spring means in response to predetermined pressure conditions set up by said arc.

4. In a circuit interrupter, a housing including two separable sections, a pair of contacts within 10 said housing one of which is movable for establishing an arc, and a spring arranged for independently actuating said movable contact to the open circuit position and resiliently holding said separable sections together. 15

5. In a circuit interrupter, a housing including a releasable closure member, a pair of contacts within said housing at least one of which is movable, an actuating member for said movable contact, a compression spring for driving said actuating member to the open circuit position to establish an arc, and a linkage mechanism operatively coupling said compression spring with said releasable closure to cause said spring to bias said closure into engagement with said 20 housing independently of the position of said actuating member. 25

6. In a circuit interrupter, a housing including a releasable closure member, a pair of contacts within said housing at least one of which is 30 movable, an operating member for said movable contact, actuating means including a compression spring, a spring support having a pair of movable plate members between which said spring is disposed, means operatively coupling 35 one of said plate members to said contact operating member for biasing said movable contact to the open circuit position, and means operatively coupling the other plate member to said releasable closure for biasing said closure toward 40 said housing. 45

7. In a circuit interrupter, a vertically disposed tubular housing, a releasable cap member seated upon the upper end of said housing, separable contacts within said housing, actuating 50 means including a spring for operating said contacts to the open circuit position, and a linkage operatively coupling said spring with said cap member for biasing the latter toward said housing, said cap member being adapted to be raised 55 from its seat against the bias of said spring in response to predetermined pressure conditions within said housing for quickly relieving the housing of said conditions. 60

8. In a circuit interrupter, a vertically disposed tubular housing, a releasable cap member seated upon the upper end of said housing, separable contacts within said housing, actuating means including a spring for operating said contacts to the open circuit position, and a linkage 65 operatively coupling said spring with said cap member for biasing the latter toward said housing, said cap member being adapted to be raised from its seat against the bias of said spring in response to predetermined pressure conditions 70 within said housing for quickly relieving the housing of said conditions, said cap member having a conically flanged seat surface for automatically aligning the cap member with said housing upon the subsidence of pressure within 75 said housing. 80

9. In a circuit interrupter, a housing containing arc-extinguishing liquid, circuit interrupting means within said housing including separable contacts for establishing an arc, liquid moving 75

- means operative for subjecting the arc path between said contacts to a flow of arc extinguishing liquid, resilient means for actuating said liquid moving means and pressure relieving means associated with said housing including a member movable to open and closed positions, said movable member being normally biased to the closed position by said resilient means and moved to the open position in response to predetermined pressure conditions within said housing.
10. In a circuit interrupter, a housing containing arc-extinguishing liquid, said housing having two separable sections, separable contacts within said housing for establishing an arc, liquid moving means operative to establish a flow of arc-extinguishing liquid in the arc path between said contacts and resilient means arranged for actuating said liquid moving means and resiliently holding said separable sections together.
15. In a circuit interrupter, a housing containing arc-extinguishing liquid, said housing having two separable sections, separable contacts at least one of which is movable for establishing an arc, a plunger member movable with said movable contact for subjecting the arc to a flow of arc-extinguishing liquid, and spring means arranged for independently actuating said plunger member and resiliently holding said separable sections together.
20. In a circuit interrupter, a housing containing arc extinguishing liquid and having a vent opening, a closure member for said opening movable to open and closed positions, separable contacts for establishing an arc within said arc extinguishing liquid, liquid moving means operative to cause a flow of arc extinguishing liquid in the path between said contacts, and spring means for biasing said closure member to the closed position and for actuating said liquid moving means, said closure member being movable to the open position against the bias of said spring means in response to predetermined pressure conditions set up by said arc.
25. In a circuit interrupter, a housing including a releasable closure member, arc extinguishing liquid in said housing, a pair of contacts within said housing, at least one of which is movable to establish an arc, a piston member carrying said movable contact and operative to move arc-extinguishing liquid into engagement with said arc, spring means to operate said piston member to open circuit position and a linkage mechanism operatively coupling said spring means with said releasable closure to cause said spring means to bias said closure into engagement with said housing independently of the position of said piston member.
30. In a circuit interrupter, a housing containing arc extinguishing liquid and having a releasable closure member, separable contacts within the housing for establishing an arc within said arc extinguishing liquid, liquid moving means operative to establish a flow of arc extinguishing liquid between said contacts, actuating means including a compression spring for operating said liquid moving means, a spring support having a pair of movable plate members between which said spring is disposed, means operatively coupling one of said plate members to said liquid moving means and means operatively coupling the other plate member to said releasable closure member for biasing said closure member toward said housing.
35. In a circuit interrupter, a vertically disposed tubular housing, a releasable cap member seated on the upper end of said housing, a quantity of arc extinguishing liquid in said housing, separable contacts immersed in said arc extinguishing liquid for establishing an arc, a piston member operative to move arc extinguishing liquid between said contacts, spring means for operating said piston member and a linkage operatively coupling said spring means with said cap member for biasing the latter toward said housing, said cap member being adapted to be raised from its seat against the bias of said spring means in response to predetermined pressure conditions within said housing for quickly relieving the housing of said conditions.
40. In a circuit interrupter, a housing containing arc-extinguishing liquid, circuit interrupting means within said housing including separable contacts, at least one of which is movable for establishing an arc, liquid moving means operative for subjecting the arc path to a flow of arc-extinguishing liquid, pressure relieving means for said housing including a member movable to open and closed positions and single resilient means for actuating said movable contact and said liquid moving means and for biasing said movable member to the closed position against the pressure within said housing.
45. In a circuit interrupter, a housing including two separable sections, arc extinguishing liquid in said housing, a circuit interrupting means including separable contacts immersed in said arc extinguishing liquid, at least one of said contacts being movable for establishing an arc, liquid moving means operative for subjecting the arc path to a flow of arc extinguishing liquid, and a single resilient means for actuating said contact and said liquid moving means and for resiliently holding said separable sections together.
50. In a circuit interrupter, a vertically disposed tubular housing, a releasable cap member seated on the upper end of said housing, a quantity of arc extinguishing liquid in said housing, separable contacts immersed in said arc extinguishing liquid at least one of said contacts being movable to establish an arc, a piston member operative for subjecting the arc path to a flow of arc extinguishing liquid, a spring means for operating said movable contact to open circuit position and for actuating said piston member, and a linkage operatively coupling said spring means with said cap member whereby said spring means biases said cap member toward said housing independently of the positions of said movable contact and piston member.

ANDREW H. BAKKEN.
